UNITED STATES PATENT OFFICE.

JAMES M. CHESNUT, OF PHILADELPHIA, PENNSYLVANIA.

FIRE-ESCAPE.

1,174,684.

Specification of Letters Patent.

Patented Mar. 7, 1916.

Application filed April 10, 1915. Serial No. 20,555.

To all whom it may concern:

Be it known that I, JAMES M. CHESNUT, a citizen of the United States, residing at Philadelphia, in the county of Philadelphia and State of Pennsylvania, have invented 5 certain new and useful Improvements in Fire-Escapes, of which the following is a specification, reference being had to the accompanying drawings.

10 This invention relates to an improved fire escape and more particularly to devices of that general character commonly known as frictional fire escapes, in which means is provided for frictional engagement upon a 15 rope to effect the descent of a person from a window.

The invention has for one of its more particular objects to provide a device of the above character which may be employed 20 either as a movable support upon which a person may descend the relatively stationary rope or which can be arranged in a stationary position upon the window sill and operated by a person within the room to permit 25 the rope to move therethrough and lower a person suspended from the rope to the ground.

The invention has for an additional object to provide a frictional fire escape including 30 an improved mounting and construction of the brake lever which permits the operator to easily and quickly control the frictional pressure upon the rope.

The invention has for a further general 35 object to improve and simplify the construction of such hand fire escapes and render the same strong, durable, and serviceable in practical use and capable of manufacture at minimum cost.

40 With the above and other objects in view, my invention consists in the novel features of construction, combination, and arrangement of parts to be hereinafter more fully described, claimed, and illustrated in the accompanying drawing, in which,

Figure 1 is an elevation illustrating one application and use of my invention; Fig. 2 is a similar view showing a different manner of using the device; Fig. 3 is an enlarged 50 longitudinal section, parts being broken away; Fig. 4 is a section taken on the line 4-4 of Fig. 3; and Fig. 5 is a detail elevation of the brake lever.

Referring in detail to the drawing, 55 designates the body of my improved fric-

tional fire escape which includes a cylindrical shank portion 6 and an enlarged central rectangular body portion 7. This central portion of the device is formed with a lateral projection whereby the horizontal shoulder 8 is produced at the inner end of the shank 6. The shank 6 is formed with a longitudinal bore, indicated at 9, and this bore, where it extends through the enlarged central portion 7 of the body, is gradually 60 narrowed or contracted, as at 10, the walls of such portions of the bore being of convex form so that the bore section 10 will be of relatively small diameter at the center thereof and gradually flare or increase in 65 diameter toward the opposite ends of the intermediate body portion 7.

The shank extension 11, projecting from the opposite side of the medial body portion 7 of the device with respect to the cylindrical shank 6, is of semi-cylindrical form and is provided at its extremity with a laterally projecting lug 12 having an opening 13 formed therein. The body portion 7 of the device is recessed on one side of the bore 80 section 10 to accommodate the rectangular head 17 of the brake lever 16. This head is fulcrumed upon the pin 18 which is fixed at its ends in the opposite sides of the body portion 7 of the device. The inner face of 85 the head 17 is formed with a longitudinally extending groove or channel 19 which also has an intermediate contracted portion 20 similar to the contracted section 10 of the bore 9, and in spaced relation thereto. The 90 brake lever 16 has its free end outwardly curved, as at 21.

The lateral extension of the body 7 is cut out or recessed to provide spaced ears in which the ends of pins, indicated at 22, are 95 secured. From these pins, the endless straps 23 are hung, and each of said straps is provided with an adjusting loop 24. By sliding said loops upon the straps, the free ends of the straps may be provided with loops 100 of various sizes for engagement around the legs or the body of the user, as will be readily understood. Upon the outer end of the cylindrical shank portion 6 of the device, an annular flange or collar 25 is 105 formed.

In the use of my invention in the manner shown in Fig. 1, the rope, indicated at R, is extended through the bore 9 and the opening 13 of the device, and one end of this rope 110

is securely attached to a hook in the window sill of the building, or to a bedstead or other suitable object in the compartment, which will serve as an anchor therefor. The 5 looped straps 23 are then engaged around the legs or one of these straps may constitute a seat and the other strap passed under the arms and around the shoulders. After the device has been attached to the body, the 10 brake lever 16 is grasped in one hand and the other hand gripped upon the cylindrical shank 6. The person then lowers himself along the rope, the speed of descent being regulated and controlled by exerting a 15 greater or less amount of pressure upon the brake lever 16. When this lever is forced inwardly toward the shank 11, it will be apparent that the pressure exerted upon the rope will cause the contracted walls of the 20 bore section 9 and of the groove 19 in the brake lever to frictionally engage with the rope and thus check the gravity movement of the device with the person suspended thereto. In this manner, it will be seen that 25 a person may easily, quickly and safely lower himself from the window of a burning building without assistance. In Fig. 2, however, I have disclosed another manner of using my invention, but which requires 30 the assistance of another person. In such use of the device, it will be noted that the shoulder 8 on the body thereof is engaged against the window sill. The rope R which is extended through the bore 9 and opening 13, is suitably looped at one end and secured around the body of the person to be lowered from the building. The other person in the room then grasps the shank 9 and brake lever 16 and places one foot in 35 one of the looped straps 23 so as to retain the device in position upon the window sill. The person to whom the rope has been attached is then lowered from the window and the speed of travel of the rope through 40 the bore 9 is regulated and controlled by the person in the room, simply by increasing or decreasing the hand pressure on the brake lever 16 in the manner above referred to.

From the foregoing description, taken in 50 connection with the accompanying drawing, it will be seen that I have produced a simple, light and compact hand fire escape device which may be readily carried by the traveler in a valise or bag, from place to place. By 55 means of the device, a person may rapidly descend, from great heights, to the ground without shock or jar. When flames are leaping up from the lower window of the building, the lower end of the rope may be 60 carried by persons on the ground to a suitable point to escape the flames, and secured

or anchored so that the person may descend safely without passing through the flames.

The flange or collar 25 on the shank 9 effectually prevents slipping of the hand 65 upon said shank so that a secure grip upon the same can be retained.

In carrying out my invention, the device may be constructed in various sizes, and of steel, cast iron, aluminum, or other metal. 70 By the provision of the outwardly turned lower end 21, the same forms a stop for the hand of the operator and prevents the same from slipping longitudinally and losing the grip upon the brake lever 16. While I have 75 referred to the preferable form and arrangement of the several structural features of my invention, it is to be understood that the same is susceptible of considerable modification therein and I, therefore, reserve the 80 privilege of resorting to all such legitimate changes as may be fairly embodied within the spirit and scope of the invention as claimed.

Having thus fully described my invention, 85 what I desire to claim and secure by Letters Patent is:—

A fire escape device of the character described including a body having a lateral extension and further provided at one side 90 thereof with a recess, a horizontal shoulder formed on said body, a cylindrical shank extending from one side of the body and constituting a hand grip, said shank and the body being longitudinally bored to receive 95 a rope, a longitudinally disposed arm extending from the side of the body opposite the shank, said arm being semi-circular in cross section, a laterally disposed lug formed at the outer end of said arm, having an 100 opening in alignment with the bore of the shank and body, the section of the bore extending through the body being contracted in diameter, a brake lever provided with a head adapted to be disposed within the recess in the body and pivotally mounted therein, said brake lever having a longitudinal groove in the inner face provided with a contracted medial portion opposed to the contracted section of the bore in said 110 body for binding frictional engagement upon the rope, said brake lever having an outwardly curved free end, and looped straps connected to the lateral projection of the body, as and for the purpose set forth. 115

In testimony whereof I hereunto affix my signature in the presence of two witnesses.

JAMES M. CHESNUT.
